US00D362235S

United States Patent [19]
Franzen

[11] Patent Number: Des. 362,235
[45] Date of Patent: ** Sep. 12, 1995

[54] DATA PROCESSING DEVICE

[76] Inventor: Jürgen Franzen, c/o German Trade
Office Tapiei, 4 F, No. 350,
Min-Sheng E. Rd., Taipei 10444,
Taiwan

[**] Term: 14 Years

[21] Appl. No.: 3,702

[22] Filed: Jan. 14, 1993

[30] Foreign Application Priority Data

Jul. 20, 1992 [WO] WIPO DM/023 399
[52] U.S. Cl. D14/100

[57] CLAIM

The ornamental design for a data processing device, as shown and described.

DESCRIPTION

FIG. 1 is a reduced perspective view of a data processing device showing my new design;
FIG. 2 is a top plan view thereof;
FIG. 3 is a rear elevational view thereof;
FIG. 4 is a bottom plan view thereof;
FIG. 5 is a right side elevational view thereof;
FIG. 6 is a left side elevational view thereof; and,
FIG. 7 is a front elevational view thereof.

Fig. 1***Fig. 2******Fig. 3******Fig. 4******Fig. 5******Fig. 6******Fig. 7***
